PATTERN

Jacob Squire, Long Island City, N. Y.

Application December 20, 1941, Serial No. 423,797

3 Claims. (Cl. 33—5)

This invention relates to patterns and more particularly to patterns used in cutting shoe upper blanks from a leather skin or other shoe upper material.

It frequently happens that shoe upper blanks for shoe uppers of various styles have the same peripheral contour but differ from each other in the provision in the different blanks of various ornamental or other cut-outs. It was, therefore, necessary hereto to provide different patterns for use in cutting blanks having different ornamental cut-outs, respectively, although in other respects the blanks may be the same. As the same style is cut in a range of sizes, this necessitated the provision of sets of the different patterns, and since more than one set of patterns for each style is required for adequate production purposes, it is readily appreciated that the cost of the patterns may mount to a high level.

The primary object of the present invention is to obviate the above described disadvantages and in particular to provide a pattern which is not limited to one style but can be used in cutting shoe upper blanks of various styles in respect to the ornamental or other cut-outs provided in different blanks, respectively.

This object of the invention and objects ancillary thereto will be understood more fully from the following description considered with reference to the accompanying illustrative drawing.

In the drawing:

Fig. 1 is a plan view of a pattern embodying the present invention;

Fig. 2 is a sectional view on the line 2—2 of Fig. 1;

Fig. 3 is a plan view of a removable part of the pattern shown in Fig. 1;

Fig. 4 is a sectional view on the line 4—4 of Fig. 3;

Fig. 5 is a view similar to Fig. 3 showing the part provided with a different form of pattern cut-out.

Referring now more particularly to the drawing, the pattern 10 embodying the present invention comprises a flat plate 12 formed of cardboard or other suitable material and having a knife-guiding edge constituted by a sheet metal edge-binding strip 14 extending completely around the peripheral edge of the pattern. As here shown pattern 10 is shaped to the contour of the shoe upper blank to be cut from the leather skin or other sheet of shoe upper material, said blank being for a pump or similar low shoe.

In accordance with the present invention, pattern 10 is constructed in such manner that with a slight change, easily effected, it can be used for cutting shoe upper blanks having any number of different shaped cut-outs which may remain open in said blanks or which may be filled with ornamental inserts. For this purpose the blank 12 of said pattern is provided with an opening 16 in which may be fitted any one of a number of auxiliary plates, for example, the plate 18 shown in Figs. 1 and 3 or the plate 18a shown in Fig. 5, said auxiliary plates being preferably formed of sheet metal. It will be understood plates 18 and 18a are merely illustrative of a number of plates which may be interchangeably fitted in plate 12 of pattern 10. It will be understood also that said auxiliary plates may be fitted in patterns of different sizes since the cut-outs to be provided in blanks of a range of different sizes may be of the same size. The cut-out openings in the auxiliary plates may vary widely in configuration, said cut-out openings indicated at 20 and 20a in plates 18 and 18a, respectively, being merely illustrative.

In Fig. 1, the auxiliary plate is shown fitted in position in the forward vamp portion of the pattern centrally between the outer side edges of the pattern, but it will be understood that plate 12 of the pattern may have the plate-receiving opening 16 positioned differently, and further it will be understood that plate 12 may be provided with more than one plate receiving opening so that the same may be used for providing shoe upper blanks of the same configuration with a plurality of cut-outs or with one or more cut-outs in various predetermined positions therein. As here shown, the auxiliary plate is provided with a pointed portion 22 and with an indicator line 24 to aid the shoe cutter in positioning the pattern in cutting the blank of shoe upper material. It will be understood that the auxiliary plate fits removably in the opening 16 therefor in the pattern, the non-circular peripheral edge 26 of said auxiliary plate engaging the non-circular peripheral edge of opening 16, and that the edge 28 of the opening in the auxiliary plate is used as a guide for the shoe cutter's knife. While the auxiliary plates indicated at 18 and 18a are illustrated in conjunction with a pattern of one configuration, it will be understood that said auxiliary plates can be used with patterns of other configurations whereby shoe upper blanks of different peripheral edge contours may have the same or different cut-outs provided therein.

Thus, it is seen that the constructions herein

shown or described are well adapted to accomplish the objects of the present invention. It will be understood, however, that while I have shown and described the preferred embodiment of my invention, the latter may be embodied otherwise than as herein shown or described and that in the illustrated embodiment certain changes in the details of construction and in the arrangement of parts may be made and will occur to skilled artisans in view of the present disclosure. Therefore, I do not wish to be limited to the invention as herein illustrated or described except to the extent which may be required by the scope of the appended claims.

Having thus described my invention, what I claim and desire to secure by Letters Patent is:

1. A pattern for use in cutting shoe upper blanks from a sheet of shoe upper material, said pattern comprising a flat plate having an outer knife-guiding edge shaped to the contour of the edge of the blank to be cut from said sheet, said plate having an opening therethrough, said opening being spaced inwardly of said knife-guiding edge and a flat plate fitting into said opening in said first mentioned plate and provided with an opening therethrough forming an internal knife-guiding edge having a contour of a part to be cut from the blank in predetermined relation to the outer edge thereof, said last mentioned plate having side edges which engage the edge of said first mentioned plate at said opening thereof for holding said last mentioned plate in predetermined relation to said outer knife-guiding edge of said first mentioned plate and against movement in the plane of said first mentioned plate.

35

2. A pattern for use in cutting shoe upper blanks from a sheet of shoe upper material, said pattern comprising a flat plate having an outer knife-guiding edge shaped to the contour of the edge of the blank to be cut from said sheet, said plate having a non-circular opening therethrough, and a flat plate fitting into said opening in said first mentioned plate and provided with an opening therethrough forming an internal knife-guiding edge having a contour of a part to be cut from the blank in predetermined relation to the outer edge thereof, said last mentioned plate having a non-circular peripheral edge which engages the peripheral edge of said first mentioned plate at said opening for holding said last mentioned plate against movement in the plane of said first mentioned plate.

3. A pattern for use in the cutting of shoe upper blanks from a sheet of shoe upper material, said pattern comprising a flat plate having an opening therein, and a flat plate fitting into said opening in said first mentioned plate and provided with an opening therethrough forming an internal knife-guiding edge having a contour of a part to be cut from the blank in predetermined relation to the outer edge thereof, said last mentioned plate being removable and replaceable by another plate having a knife-guiding edge of a different contour, said last mentioned plate having a peripheral edge which engages the edge of said first mentioned plate at said opening for holding said last mentioned plate against movement in the plane of said first mentioned plate,

JACOB SQUIRE.
